UNITED STATES PATENT OFFICE

SUSAN M. HIBBARD, OF GENEVA LAKE, WISCONSIN, ASSIGNOR TO CATHARINE NICHOLS, EMELINE C. WEBSTER, AND FRANCIS S. EASTMAN, OF CHICAGO, ILLINOIS.

IMPROVEMENT IN FEATHER DUSTERS.

Specification forming part of Letters Patent No. 177,939, dated May 30, 1876; application filed November 13, 1874.

To all whom it may concern:

Be it known that I, SUSAN M. HIBBARD, of Geneva Lake, in the county of Walworth and State of Wisconsin, have invented new and useful Improvements in Feather Dusters, of which the following is a full description, reference being had to the accompanying drawings, in which—

Figure 1 is an elevation of a feather duster, and Fig. 2 a view of the inside of a feather with the stem partly split or cut away.

Heretofore it has been found impracticable, in manufacturing feather dusters and similar articles, to use the strong, stiff feathers of the wings and tails of turkeys, geese, &c., for, owing to the stiffness of the stems and the liability of such feathers to be broken or permanently bent, they soon become worthless.

The object of my invention is to overcome these difficulties; and its nature consists in the improvement of feather dusters as an article of manufacture, by making them of feathers split as hereinafter described.

In the drawings, A represents the fiber of the tail-feather of a turkey; B, the stem, and C the portion to be removed, which is shown partly cut away in Fig. 2.

The stems are cut away by means of any ordinary pocket-knife; but in order to do it accurately and expeditiously a knife with a gage to regulate the depth of the cut, like a splitting-knife or spokeshave, is preferable.

The advantages of cutting away the stem are, that the feather is left pliable and flexible, and can be bent in any direction without breaking; and it enables me to make feather dusters from feathers which have heretofore, owing to their stiffness, been worthless for that purpose.

When these prepared feathers are made into dusters, as shown in Fig. 1, they are wound upon and fastened to the handle in the usual way.

What I claim as new is as follows:

As an improved article of manufacture, a feather duster having the stems of the feathers split longitudinally, and a part thereof severed from the remaining part, substantially as specified.

SUSAN M. HIBBARD.
